J. TASEFF

HANGER FOR SUSPENDED CEILINGS

Filed March 30, 1925

John Taseff

John Fassett
BY
A. Martell
ATTORNEY.

UNITED STATES PATENT OFFICE.

JOHN TASEFF, OF LOS ANGELES, CALIFORNIA.

HANGER FOR SUSPENDED CEILINGS.

Application filed March 30, 1925. Serial No. 19,322.

To all whom it may concern:

Be it known that I, JOHN TASEFF, a citizen of the United States, residing at Los Angeles, in the county of Los Angeles, State 5 of California, have invented new and useful Improvements in Hangers for Suspended Ceilings, of which the following is a specification.

My invention relates to hangers for suspended ceilings for use in large buildings of modern concrete construction.

The primary object of my invention is to provide a hanger which may be fixed in the beams or concrete floorwork of buildings 15 so as to extend downwardly therefrom and serve as supporting means for the usual ceiling framework to which the metal lath is attached.

Another object is to provide hangers of a 20 form which will facilitate the operation of suspending channel iron cross-bars which form the framework of the ceiling and thus save time and labor.

Other objects and advantages will appear 25 hereinafter and while I show herewith and will describe a preferred form of construction I desire it to be understood that I do not limit myself to such preferred form but that various changes and adaptations may 30 be made therein without departing from the spirit of my invention as hereinafter claimed.

In the drawings which accompany this 35 specification:

Fig. 1 is a view, partly in section, of one 35 form of my improved hanger, fixed in the concrete floorwork.

Fig. 2 is a view similar to Fig. 1 showing 40 a slightly modified form of hanger and illustrating the positions of the channel iron bars held therein.

Fig. 3 is a view similar to Fig. 1 showing 45 a hanger of slightly different form.

Fig. 4 is a view similar to Fig. 3 showing 50 the same form of supporting member with modified shank and anchor parts, also illustrating the positions of the channel irons in the hook member.

Fig. 5 is an enlarged view in perspective 55 of the socket forming part of the hanger shown in Fig. 1.

Fig. 6 is a view similar to Fig. 5 showing the socket which forms part of the hanger shown in Fig. 2.

Fig. 7 is a view similar to Figs. 5 and 6 55 showing the socket which forms part of the hanger shown in Fig. 3.

Figs. 8 and 9 are views in perspective of similar hanger parts which may be substituted for some of those shown in the other 60 figures.

Fig. 10 is a side view of another form of anchor piece and suspending hook.

Fig. 11 is a side view of a single piece 65 hanger of the same general form as Fig. 4 but of different construction.

Fig. 12 is a fragmentary plan view of the ceiling, illustrating the appearance of a pair of channel irons in a hanger of the type shown in Fig. 4 as seen from below and a 70 method of attaching metal lath to the channel irons.

Referring to the parts in detail the form of hanger shown in Fig. 1 consists of a hollow metal socket 10 having a shank 11 and 75 a cross bar 12 adapted to be imbedded in the floorwork of a building so that the socket opening is flush with the under side thereof; a hook member 13 adapted to receive the channel irons and a supporting rod 14 adapted to connect the hook member and the socket member and to hold the former suspended in spaced relation to the latter. The socket member 10 is provided with a slot 15 having a widened portion 16 shown 85 in Fig. 5 to admit a bolt head for use in suspending water pipes and the like. A transverse bar 17 is fixed inside the socket near one end of the slot. The hook member 13 is preferably a cast metal block having a short up-turned hook 18 on one side of its lower end and a relatively long up-turned hook 19 just above said short hook, set at right angles thereto. The upper end of the block has a screw-threaded hole to receive the 90 suspending rod 14 which has its lower end screw-threaded to engage therewith and has a hook 20 adapted to engage transverse bar 17.

The hanger shown in Fig. 2 is similar to 100 that shown in Fig. 1 except that the socket 21 has a hooked lug 22 projecting from one

of its inner sides instead of a slot and transverse bar, and is anchored in the concrete by a heavy wire 23 extending through ears 24 and bent upwardly and outwardly to form anchor pins 25. The hook member 13 has its upper end reduced to form a lug 26 which has an aperture 27 to receive a hook 28 on the lower end of the suspending rod 29, the upper end of which has an eye 30 adapted to slip over hooked lug 22, there being sufficient space between this lug and the opposite side of the socket to admit said eye as shown in Fig. 6.

The modified hanger shown in Fig. 3 differs from those shown in Figs. 1 and 2 in that a different form of socket is used and the hook member is made so that it connects directly with the socket without a suspending rod. The socket is a block 31 of the form shown in Fig. 7 with a deep groove 32 in its under face and a vertical aperture in the center thereof through which an eye bolt 33 extends with the eye part 34 set transversely of the groove and the upper end 35 bent at a right angle to form an anchor pin. The hook member 36 is made of a piece of angle iron which is split at its lower end and the flange parts bent upward to form hooks 37 and 38 corresponding to hooks 18 and 19 respectively in Figs. 1 and 2. The upper end is reduced and bent to form a hook 39 adapted to engage with eye 34.

The hanger shown in Fig. 4 is similar to that shown in Fig. 3 except that no socket is required in this case, the shank 40 of the hook member being extended upwardly to form an anchor. This is done by splitting the upper end of the angle iron, collapsing the flanges along the part to be imbedded as at 41 and bending them apart at the upper end to form anchor lugs 42. A pin 43 extending through a hole in part 41 serves to hold the hanger in its properly adjusted position in the forms when the concrete is being poured.

Figs. 7 and 8 show similar anchor parts made of strap iron the upper ends of the pieces being split and the ends being bent in opposite directions to form anchor lugs 44. A loop 45 may be made at the form line 46 and a link 47 held therein may serve as an eye for engaging a hook 48 on a suspending strap 49, which may have hooks similar to those described formed on its lower end. Or the anchor piece may be extended below the form line as at 50 and holes 51 made therein in which bolts or rivets may be used to connect the hook member or other parts.

Fig. 10 shows an anchor piece 52 with a screw-threaded socket 53 adapted to be set in the concrete flush with the form line, so that a suspending rod 54 with a threaded upper end 55 may be screwed into it.

Fig. 11 shows a single piece hanger simi-

lar to the one shown in Fig. 4 but made of thick wire or thin rod material. The piece is bent near its middle to form an anchor loop 56, has a right angled return bend 57 at the form line and the ends extend downwardly and are bent into hooks 58 and 59, corresponding to hooks 37 and 38 respectively in Figs. 3 and 4.

The channel irons are placed in the hooks as indicated in Figs. 2, 4 and 11, the upper series being parallel to each other and at right angles to the lower series which are also parallel to each other. It being most convenient to place the upper series first it is evident that the bars 60 of this series must be lifted somewhat in order to allow the bars 61 of the lower series to be passed into the lower hooks. The upper hooks are made longer than the lower ones to provide for such lifting of the upper bars without their becoming disengaged therefrom.

As shown in Fig. 12 the metal lath 62 is applied directly to the channel irons and is attached thereto by pieces of wire looped around the irons at intervals so that their ends project downwardly through the meshes of the lath and are twisted together to form a closed loop 63.

It is evident that some of the parts shown are interchangeable, that is, the socket parts and anchor parts may be used with other associated parts than those shown.

Having described my invention, I claim:

1. A hanger for suspended ceilings comprising a hook member adapted to be fixed in the floorwork of a building so as to extend therebelow, a short up-turned hook on the lower end of said hook member and a longer up-turned hook adjacent said short hook but above it and at an angle of 90 degrees thereto.

2. A hanger for suspended ceilings comprising a socket member and a hook member, said socket member being adapted to be anchored in the floorwork of a building so as to be flush with the under side thereof and said hook member being adapted to connect with said socket member so as to extend therebelow, a short up-turned hook and a longer up-turned hook formed on said hook member, said short hook being on the lower end thereof and said longer hook being adjacent said short hook but above it and at an angle of 90 degrees thereto.

3. A hanger for suspended ceilings comprising a socket member adapted to be anchored in the floorwork of a building so as to be flush with the underside thereof, a hook member adapted to support the framework of a ceiling and a suspending rod adapted to connect said hook member to said socket member and to hold the former in spaced relation to the latter; a short up-turned hook and a longer up-turned hook formed on said hook member, said short

hook being on the lower end thereof and said longer hook being adjacent said short hook, but above it and at an angle of 90 degrees thereto.

5 4. In combination with the floorwork of a building a hanger for suspended ceilings comprising a socket imbedded in the floor-work so as to be flush with the under side thereof, and a hook member attached to said

socket so as to be held in spaced relation 10 thereto; a short up-turned hook and a longer upturned hook formed on said hook member, said short hook being on the lower end of said hook member and said longer hook being adjacent said short hook but above it 15 and at an angle of 90 degrees thereto.

JOHN TASEFF.
